UNITED STATES PATENT OFFICE.

JAMES VALK, OF TOPEKA, KANSAS.

CENTRIFUGAL PUMP.

961,993.

Specification of Letters Patent. Patented June 21, 1910.

Application filed March 16, 1910. Serial No. 549,655.

To all whom it may concern:

Be it known that I, JAMES VALK, a citizen of the United States, residing at Topeka, in the county of Shawnee and State of Kansas, 5 have invented a new and useful Centrifugal Pump, of which the following is a specification.

This invention relates to centrifugal pumps and is more particularly an improvement upon the structure disclosed in Patent 10 No. 933,681, issued to me on September 7, 1909.

One of the objects of the invention is to provide an impeller in the form of a flat 15 wheel arranged for rotation within a casing provided therefor, the said impeller having means whereby water or other liquid operated upon thereby will be expelled therefrom by centrifugal force and carried in a 20 circular path concentric with the impeller and finally discharged through an outlet orifice provided therefor.

A further object is to provide a pump of this character which dispenses with the use 25 of a check valve in the inlet and which is, instead, provided with valves carried by the impeller and which are arranged to automatically open under the action of centrifugal force.

30 A still further object is to provide an impeller having a series of compartments therein for the reception of bodies of water to be discharged from the pump, each of the said compartments being formed with an air 35 vent whereby air is prevented from becoming trapped within the impeller.

Another object is to provide an impeller having valves which are designed not only 40 to close the outlet ports of the impeller during the priming of the pump, but which also, at the same time, close the air vents.

With these and other objects in view the invention consists of certain novel details of construction and combination of parts 45 hereinafter more fully described and pointed out in the claims.

In the accompanying drawings the preferred form of the invention has been shown.

In said drawings:—Figure 1 is a vertical 50 transverse section through a pump constructed in accordance with the present invention. Fig. 2 is a section on line A—B Fig. 1.

Referring to the figures by characters of 55 reference 1 designates a base adapted to be bolted or otherwise secured upon a support-

ing structure and this base is formed with standards 2 in which is journaled a shaft 3, said shaft being provided with a pulley 4 or the like located preferably between the 60 standards and adapted to be driven by any suitable motor.

The shaft 3 projects through a bearing 5 formed at the center of a plate 6 which constitutes one side of the pump casing, this 65 casing being made up, in addition to the plate 6, of a plate 7 having a rounded marginal portion 8 the free edge of which is bolted or otherwise fixedly secured to the 70 marginal portion of the plate 6. The casing thus formed is in the shape of a volute and the rounded marginal portion thereof merges into a tangentially disposed outlet extension 9. A central opening 10 is formed 75 within the plate 7 and extending around this opening and laterally from the plate is a cap 11 which serves to support one end of a feed pipe 12. A recess 13 is formed with- 80 in the center of the inner face of plate 6 at a point directly opposite the opening 10 and the shaft 3 projects into this recess. In order that the casing may be held fixed 85 relative to the base 1, a bracket 14 is secured to the base and to the plate 6 or, if preferred, this bracket may constitute an integral part of the plate.

The impeller is preferably in the form of a one piece hollow disk or wheel such as has been indicated at 15 and has a central boss 16 upon one side thereof and which is journaled within the recess 13, said boss being 90 engaged by the shaft 3, so that, when said shaft is rotated, the impeller will also be rotated.

An inlet opening 17 is formed in the center of the impeller and directly opposite the boss 16, and a tubular extension 18 is arranged about this opening and extends laterally from the wheel 15 and around the end of the feed pipe 12. A flange 19 may 100 be formed upon the free end of this tubular extension and a ring 20 may be adjustably connected to said flange for the purpose of holding a packing ring 21 in position between the tubular extension 18 and the feed 105 pipe 12. As shown in Fig. 1 the cap 11 serves to conceal the extension 18 and the parts connected to it.

Discharge openings 22 are formed in the periphery of the wheel at regular intervals 110 and arcuate webs 23 are formed within the wheel and extend from the inlet opening 17

to the respective outlet openings 22. These webs are curved outwardly in a direction opposite to that in which the wheel is adapted to rotate and compartments 24 are formed between the webs, the transverse area of each compartment gradually diminishing toward its outlet 22 from an intermediate point. It will be noted by referring to Fig. 2 that each of the webs 23 gradually merges into the peripheral wall of the wheel and that the adjoining webs thus cooperate to form nozzles through which water may be discharged along lines substantially concentric with the periphery of the casing in which the wheel is mounted.

Each of the webs 23 has an air vent 25 therein and adjacent the outlet opening 22, and a valve 26 is pivotally connected to the peripheral portion of the wheel close to each outlet and is adapted to be normally held, by centrifugal force, within a recess 27 provided therefor. The valves are so located and proportioned that when they are swung inwardly toward the center of the wheel, they will contact with the adjoining webs 23 so as to close the outlets of the compartments 24 and also close the air vents 25.

In operating the pump the same is first primed and is then driven by any suitable motor provided therefor so as to cause the impeller 15 to rotate at a high speed within its casing. The extension 18 will of course rotate upon the stationary feed pipe 12 and centrifugal force will cause the valves 26 to become seated within the recesses 27. At the same time the water or other liquid will be discharged through the compartments 24 and the outlets 22 in the form of jets which are directed along lines substantially concentric with the periphery of the impeller. The said impeller thus not only acts to throw the water outwardly by centrifugal force and thus establish a suction through the feed pipe 12, but also forces the discharged water in a substantially circular path within the volute and directs it outwardly through the discharge extension 9. During the initial operation of the pump, the air contained within the compartments 24 will be free to escape through the vents 25 and inasmuch as these vents are very small, the leakage of water therethrough subsequent to the discharge of the air, will not in any wise reduce the efficiency of the pump.

In order that the pump may exert a constant and uninterrupted pull or suction upon the water being elevated, it has been found desirable to make the central inlet opening 17 of greater area than the outlet opening in the casing and the combined areas of the outlets 22 greater than the area of the casing outlet and less than the area of the impeller inlet. For example, should the diameter of the impeller inlet be five

inches and the diameter of the casing outlet four inches, it has been found, by actual test, that best results are obtained by so proportioning the outlets of the impeller, that, when their areas are combined, they are equal to an outlet opening four and one-half inches in diameter.

Attention is called to the fact that the impeller is in the form of a flat disk having a continuous peripheral portion interrupted solely by the outlet openings 22, this being an important feature inasmuch as said continuous marginal portion results in the elimination of practically all undesirable friction of water upon the parts of the pump especially in view of the fact that the impeller discharges the water tangentially therefrom and carries it in a substantially circular path.

By referring to Fig. 2 of the drawings it will be seen that the webs 23 do not project beyond the margin of the impeller inlet but, instead, terminate at the inlet and outlets that is to say, the webs 23 do not project into the margin or within the contour of the inlet and said webs at their outer ends do not project beyond the periphery of the impeller. As a result of this construction any undesirable churning action such as would result should the webs be extended partly across the impeller inlet, is entirely eliminated.

In order that the various valves 26 may be held close while the impeller is at rest springs 28 are connected to the said valve and to the peripheral portion of the impeller. These springs are very light and when the impeller is operated, they will not be sufficiently strong to prevent the valves from being moved by centrifugal force into their seats or recesses 27.

It is of course to be understood that various changes may be made in the construction and arrangement of the parts without departing from the spirit or sacrificing any of the advantages of the invention as defined in the appended claims.

What is claimed is:

1. In a centrifugal pump an impeller having a series of water compartments, each compartment having a central inlet, a peripheral outlet, an intermediate enlarged portion and an air vent in said enlarged portion.
2. In a centrifugal pump, an impeller having a plurality of water compartments extending from a central inlet to peripheral outlets, there being an air vent within a wall of each compartment, and separate means for closing the vents during the priming of the pump.
3. In a centrifugal pump, an impeller having a plurality of water compartments, each having a central inlet, a peripheral outlet and an intermediate enlarged portion, each

compartment being provided with means for permitting the escape of air from the enlarged portion thereof.

4. In a centrifugal pump, an impeller having peripheral outlets and a central inlet, webs within the impeller extending in a regular unbroken curve from the inlet to a point in the periphery, which is the rear edge of an outlet, thence coincident with the periphery to the forward edge of the next following outlet, whereby water compartments diminishing in cross sectional area from an intermediate point to the outlet are formed between adjacent webs and the water is delivered from said compartments in the direction of a tangent to the impeller.

5. In a centrifugal pump a casing having a central inlet and a peripheral outlet, an impeller eccentrically mounted within the casing and having a central inlet and peripheral outlets, said impeller having water compartments extending from its inlet to its outlets for directing liquid by centrifugal force into the casing and along lines substantially tangential with the impeller, each compartment having an air vent therein and a valve mounted within each outlet in the impeller and adapted to close the air vent of the next succeeding compartment.

6. A centrifugal pump having an impeller formed with a plurality of compartments each provided with an inlet, an outlet, an outer wall curved on the segment of a circle having the axis of the impeller for its center, and a forward wall extending inward from the forward end of the outer wall, the outer wall and the forward wall being of substantially the same length.

40 7. In a centrifugal pump, an impeller having compartments provided with peripheral outlets and air vents, and a valve for simultaneously closing each of the outlets and the adjoining vent.

45 8. In a centrifugal pump, an impeller having a central inlet and peripheral outlets, there being water compartments between the inlet and the outlets, each compartment having an air vent adjacent one of the outlets, and a valve movably mounted within the outlet and adapted to simultaneously close said outlet and the adjoining vent.

9. In a centrifugal pump, an impeller having compartments provided with peripheral outlets for discharging liquid along lines substantially parallel with the periphery of the impeller, each compartment having an air vent therein, and a valve mounted within each outlet and adapted to be opened by centrifugal force, each of said valves when closed, being adapted to close the air vent of the next succeeding compartment.

60 10. In a centrifugal pump, an impeller having peripheral outlets for directing water or other liquid along lines substan-

tially parallel with the periphery of the impeller, air vents within the impeller, and a valve for closing each outlet and an adjoining vent, said valves being adapted to be opened by centrifugal force during the 70 operation of the impeller.

11. A centrifugal pump including a casing, an impeller having an inlet, said casing being provided with an outlet of less area than said impeller inlet, and there being 75 marginal outlets in the impeller of a combined area less than the inlet and greater than the outlet.

12. A centrifugal pump having an impeller which is circular in cross section and 80 provided with a plurality of compartments each having a forward wall and an outer wall coincident with the periphery of the impeller, the length of the outer wall of each compartment bearing approximately the 85 same fractional relation to the entire circumference of the impeller as one compartment bears to the entire number of compartments.

13. In a centrifugal pump, an impeller 90 having a series of water compartments, each compartment having a central inlet and a peripheral outlet, webs forming the outer and forward walls of each compartment, each web having a cut away portion at the 95 inner portion of its outer end, a valve in each compartment for the outlet thereof, each valve being pivoted on the outer end of one of said webs and being adapted to swing into the cutaway portion thereof, the 100 web serving to limit the outward swinging movement of the valve.

14. A centrifugal pump including a casing having an outlet, an impeller therein having a series of compartments, and an 105 inlet in communication with the inner end of each of said compartments, each compartment being provided at its outer end with an outlet, the outer wall of each compartment being curved on the segment of a 110 circle having the axis of the impeller for its center and the forward wall of each compartment being curved outward from the inlet of the impeller to the forward end of the outer wall of the compartment, the 115 combined areas of the outlets of the compartments being greater than the area of the outlet from the casing and the area of the inlet being greater than the combined areas of the outlets of said compartments. 120

15. In a centrifugal pump, an impeller including a flat circular disk having a central circular inlet in one side and peripheral outlets, there being compartments within the disk and extending from the inlet to the outlet, the combined areas of the outlets being less than the inlet, and a pump casing having an outlet of less area than the combined areas of the outlets of the impeller. 125

16. A centrifugal pump having an im- 130

5 peller which is circular in cross section and is provided with a central inlet and water compartments occupying the entire cross section of the impeller excepting the inlet, said compartments being separated from each other by walls, each wall having a forward and an outer portion of substantially the same length, the outer portion of each wall being curved on the segment of a

circle having the axis of the impeller for its center.

In testimony that I claim the foregoing as my own, I have hereto affixed my signature in the presence of two witnesses.
